UNITED STATES PATENT OFFICE.

SAMUEL V. KENNEDY AND CHARLES S. SHARP, OF AUBURN, NEW YORK,
ASSIGNORS TO D. M. OSBORNE AND COMPANY, OF AUBURN, NEW YORK,
A CORPORATION OF NEW YORK.

GRAIN-DIVIDER FOR HARVESTERS.

SPECIFICATION forming part of Letters Patent No. 760,743, dated May 24, 1904.

Application filed December 1, 1903, Serial No. 183,313. (No model.)

To all whom it may concern:

Be it known that we, SAMUEL V. KENNEDY and CHARLES S. SHARP, citizens of the United States, residing at Auburn, in the county of Cayuga and State of New York, have invented 5 certain new and useful Improvements in Grain-Dividers for Harvesters, of which the following is a full, clear, and exact description.

The object of our invention is to provide a 10 divider that can be quickly and easily removed for storage or transportation.

Referring to the accompanying drawings, Figure 1 is an end elevation of a harvester-platform, showing the divider in place. Fig. 15 2 is a similar view showing the divider and grain-wheel arranged for transportation. Fig. 3 is a detail section looking from the rear on the line $\alpha\alpha$ of Fig. 1. Fig. 4 is a detail section on the line $\gamma\gamma$ of Fig. 1. Fig. 5 is a detail 20 tail in plan of a bracket that is secured to the outer end of the finger-bar. Fig. 6 is a detail in plan of the rear portion of the divider-supporting bar, and Fig. 7 is a detail of the socket for temporarily holding the standard 25 of the divider-board.

A is the grain-wheel end of a harvester-platform, to which is secured the grain-wheel guide B.

C is the finger-bar, and D a casting bolted 30 thereto and having attached to it the forward end of a brace-bar E, which passes over the grain-wheel guide B, to which it is secured by suitable bolts, its rear end being bolted to the rear corner of the platform A.

Rigidly secured to the grainward end of the finger-bar C and integral with the first guard-finger a is a bracket a' , having upon it a lock F, which engages with the supporting-bar H and holds it against lateral movement. The 40 lock F comprises a casting f , bolted to the bracket a' , and incloses a bolt or plunger f' , which is held down in a locked position by a coiled spring g , which surrounds the bolt, one end of said spring engaging with a pin g' in 45 the bolt and the other end with the inner top of the casing.

G is the divider-point, to which the forward end of the divider-board A' is bolted. A sup-

porting-bar H is secured to the divider-point G by a horizontal pivot b , and its rear end 50 projects and is guided rearwardly in a slot e in the casting D. To prevent a movement of the bar H too far forward, we provide a casting or stop b' , which is bolted to the bar H. A standard I supports the divider-board and 55 is rigidly fastened to it.

The stop b' has an opening c , which when the divider is in operative position is directly beneath and in line with a similar opening c' in the top of the casting D. An inclined surface is formed at the point d on the inner side 60 of the casting D, against which the end of the standard I rests when the divider is in place ready for work. Secured to the brace-bar E is a casting d' , having a socket for reception 65 of the end of the standard I when the divider is drawn rearwardly for storage purposes or transportation.

It will be assumed that the divider and its several parts are in the position shown in Fig. 70 2, with the supporting-bar withdrawn from the lock F, and it is desired to place them as shown in Fig. 1. The divider-board A' is raised, swinging upon the pivot b , until the standard I is withdrawn from the socket in 75 the casting d' . The board is then moved forward, the supporting-bar H sliding in the slot e . When the bar has been adjusted in the lock F and the stop b' is in contact with the casting D, the holes or openings $c c'$ are 80 brought in alinement and a hole e' in the supporting-bar H, some distance forward from its rear end, registers with the bolt of the lock F. Then the standard I is passed through the 85 openings $c c'$. Its lower end, resting upon the incline at d , tends to form a jam-lock for the end of the supporting-bar H by forcing said bar against the side of the guide-slot e , as will be understood. The divider is thus held securely in working position. To dismount 90 the divider for storage or transportation, the divider-board A' is raised, freeing the inner end of the supporting-bar H by removing the standard I from engagement therewith. The bolt of the lock F is then raised, and the bar 95 H is free to be moved to the rear in the guide-

slot *e* until the standard *I* is in position to be inserted in the socket in the casting *d'*, holding the divider as shown in Fig. 2. If it is desired to remove the divider from the harvester, the casting or stop *b'* is unbolted from the supporting-bar *H*, when the latter can be drawn out through the guide, the bolt *f'* having been raised and the standard *I* withdrawn.

Having thus described our invention, what we claim, and desire to secure by Letters Patent, is—

1. In a harvester, the combination of a divider having a rearwardly-extending supporting-bar, a finger-bar, a guide for the supporting-bar upon said finger-bar, a divider-standard and means by which the divider-standard locks the supporting-bar in the guide.

2. In a harvester, the combination of a divider having a rearwardly-movable supporting-bar, a finger-bar, a guide for the supporting-bar upon the finger-bar, a divider-standard and means by which the standard holds the supporting-bar in its forward position.

3. In a harvester, the combination of a divider having a support movable rearwardly in a horizontal plane, a finger-bar, a guide for the support on the said finger-bar, said guide having a vertical opening therein, a casting on the support having an opening to register with the vertical opening in the guide, and a standard on the divider to pass through said openings to hold the support and divider from rearward movement.

4. In a harvester, the combination of a divider having a rearwardly-extending support, a finger-bar, a guide for the support on the finger-bar, said guide having a vertical opening therein, an opening on the support, an inclined surface on the guide, and a standard on the divider to pass through said openings and engage with the inclined surface to lock the divider in its forward position.

5. In a harvester, the combination of a divider having a rearwardly-movable support, a guide through which the rear end of said support moves, a finger-bar and a lock thereon forward of the guide to hold the front part of the support from lateral movement.

6. In a harvester, the combination of a divider having a support movable rearwardly in a horizontal plane, a finger-bar, a guide upon the finger-bar through which said support moves, a standard on the divider, a plat-

form-brace having a casting thereon and a socket in said casting in which the standard rests when the divider has been moved to its rearward limit.

7. In a harvester, the combination of a divider having a rearwardly-extending support movable rearwardly in a horizontal plane, a finger-bar, a guide upon the finger-bar through which said support moves, a standard on the divider, a platform member having a casting thereon, and a socket in said casting in which the standard rests when the divider is in its rearward position.

8. In a harvester, the combination of a divider having a support movable rearwardly in a horizontal plane, said divider being secured to said support by a horizontal pivot, a finger-bar, a guide through which the support moves, a vertical opening in the guide, an opening in the support to register therewith, a standard on the divider to pass through said openings to hold the divider in its forward position, and a lock on the finger-bar to prevent lateral movement of the support.

9. In a harvester, the combination of a divider having a rearwardly-extending supporting-bar, bearings on the harvester in which the bar is mounted to slide so as to permit the divider to be adjusted forward into operative position or rearward into inoperative position and a divider-board pivotally connected to the forward part of the supporting-bar so as to fold upward when the bar is drawn rearward.

10. In a harvester, the combination of a divider having a rearwardly-extending supporting-bar and a divider-board pivotally connected to the forward end thereof, bearings on the harvester in which the bar is slidably mounted so as to permit the divider to be adjusted forward into operative position or rearward into inoperative position, a supporting standard for the divider-board, and bearings on the harvester to receive the standard in either position of adjustment of the divider.

In testimony whereof we hereunto set our hands, this 19th day of November, 1903, in the presence of two attesting witnesses.

SAMUEL V. KENNEDY.

CHARLES S. SHARP.
